Primary Examiner—Terry A. Wallace

(21) Appl. No.: **29/145,287**

(74) Attorney, Agent, or Firm—Donald R. Schoonover

(22) Filed: **Jul. 20, 2001**

(57) **CLAIM**

(51) LOC (7) Cl. **07-99**

I claim the ornamental design for an electrically heated ice cream scoop, as shown and described.

(52) U.S. Cl. **D7/680**

DESCRIPTION

(58) **Field of Search** D7/681, 646, 691,
D7/692, 393-395; 30/324-328; 294/55;
425/276, 279, 283-286, DIG. 13; 16/110.1

(56) **References Cited**

FIG. 1 is a perspective view of the electrically heated ice cream scoop embodying the design of the present invention.
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.
